FUEL MIXER FOR INTERNAL COMBUSTION ENGINES

Filed Aug. 21, 1926

INVENTOR

Harry Wayte
Chappell & Carl
ATTORNEYS

UNITED STATES PATENT OFFICE.

HARRY WAYTE, OF KALAMAZOO, MICHIGAN.

FUEL MIXER FOR INTERNAL-COMBUSTION ENGINES.

Application filed August 21, 1926. Serial No. 130,698.

The main object of this invention is to provide a gaseous fuel mixer adapted to be interposed between the intake pipe of a manifold and a carburetor which is very effective in preventing the passage of unvaporized fuel into the manifold and at the same time offers a minimum of obstruction in the passage.

A further object is to provide a device having these advantages which does not become clogged.

Objects pertaining to details and economies of my invention will definitely appear from the detailed description to follow.

15 The invention is clearly defined and pointed out in the claims.

A structure embodying the features of my invention is clearly illustrated in the accompanying drawing forming a part of this 20 application, in which:

Fig. 1 is a side view of a carburetor and manifold with my improved fuel mixer in operative relation thereto, the carburetor and manifold being indicated conventionally 25 by dotted lines.

Fig. 2 is a front view of my improved mixing device.

Fig. 3 is a fragmentary vertical central section through the discharge of a carburetor 30 and the intake of a manifold with my device in operative relation thereto.

Fig. 4 is a fragment of the filling material preferably employed by me.

Fig. 5 is a front view of a slightly modified form of my improved mixer.

Referring to the drawing, 1 represents a carburetor and 2 the intake manifold of an internal combustion engine. The carburetor is provided with an attaching flange 4 while 40 the manifold has a coacting attaching flange 5.

My improved mixer comprises a plate-like holder 6 adapted to be interposed between the flanges 4 and 5, the plate having openings 7 registering with the carburetor and manifold passages. I provide a receptacle 8 formed of wire screen and a cover 9 also formed of screen. The edges of the receptacle and cover are engaged in the annular 45 groove 10 in the plate 6, the edges being sprung into this groove or retained therein

by the resilience of the material forming these parts.

Within this receptacle is a filler material 55 designated generally by the numeral 11 formed of a fabric 12 knitted from non-corrodible strands preferably of copper, the fabric being loosely crumpled upon itself and arranged in the holder so as not to offer any considerable obstruction to the passage 60 of air, but does serve to collect and mix with the air any unvaporized fuel.

The receptacle is preferably rearwardly tapered as illustrated and when disposed in a horizontal position as shown in Fig. 1, 65 the upper wall 13 of the receptacle has a greater inclination than the other walls as shown in Fig. 3 so that there is less of a body of the filling material at the top of the passage. This affords a minimum of obstruction to the passage of the carbureted air and the heavier unvaporized fuel being carried along in the lower part of the passage is caught by the filling material and 70 mixed or vaporized. Where the device is to occupy a horizontal position I do not distort the receptacle, it being regular in form 75 as indicated at 14 in Fig. 5.

My improved mixing device is highly efficient, does not become clogged and offers 80 comparatively little obstruction to the passage of the air.

Having thus described my invention what I claim as new and desire to secure by Letters Patent is:

1. A device of the class described comprising a plate-like support adapted to be interposed between the intake pipe of a manifold and a carburetor and having an opening 90 therein registering therewith, the edge of the opening having an annular groove therein, a receptacle and a cover therefor formed of wire screen disposed with their edges in said groove, said receptacle being disposed to project into the manifold and being rearwardly tapered, and a filling of knitted metal strands crumpled loosely and arranged in said receptacle, the upper wall of said receptacle having an inclination substantially 95 greater than the other walls thereof so that there is less obstruction at the top than at the bottom of the device.

2. A device of the class described comprising a plate-like support adapted to be interposed between the intake pipe of a manifold and a carburetor and having an opening 5 therein registering therewith, the edge of the opening having an annular groove therein, a receptacle and a cover therefor formed of

wire screen disposed with their edges in said groove, and a filling of knitted metal strands crumpled loosely and arranged in said receptacle. 10

In witness whereof I have hereunto set my hand.

HARRY WAYTE.
